DESIGN FOR A COMBINED BILLFOLD, CHANGE PURSE AND KEYHOLDER

Samuel J. Smallman, New York, N. Y.

Application September 8, 1944, Serial No. 115,225

Term of patent 14 years

(Cl. D87—3)

To all whom it may concern:

Be it known that I, Samuel J. Smallman, a citizen of the United States of America, residing in city of New York, county of New York, and State of New York, have invented a new, original, and ornamental Design for a Combined Billfold, Change Purse, and Keyholder, of which the following is a specification, reference being had to the accompanying drawing, forming part thereof.

Fig. 1 is a front view slightly in perspective of a combined billfold, change purse, and keyholder

showing my new design with the change purse which is detachable in closed position.

Fig. 2 is a fragmentary view slightly in perspective of the right side of the article shown in Fig. 1 with the change purse removed.

The back of the billfold is substantially plain.

I claim:

The ornamental design for a combined billfold, change purse, and keyholder, substantially as shown and described.

SAMUEL J. SMALLMAN.
